UNITED STATES PATENT OFFICE

ROBERT MACLEAN, OF CHICAGO, ILLINOIS, ASSIGNOR TO AMALGAMATED ROOFING COMPANY, OF CHICAGO, ILLINOIS, A CORPORATION OF ILLINOIS

ROOFING

Application filed January 23, 1930. Serial No. 422,740.

My invention relates to roofing and more particularly to an improved outer roof covering made up of shingles. It includes among its objects and advantages the maximum of simplicity in connection with laying a roof having an arbitrary design or pattern built into the roof as distinguished from a design or pattern usually of smaller dimensions applied to the pieces of material from which the roof is built up.

10 In the accompanying drawings:

Figure 1 is a plan view of one type of shingle involved in the invention;

15 Figure 2 is a plan view of a shingle identical with Figure 1, except as to color; and

Figure 3 is a plan view of another shingle of the same size and shape, but of still another color arrangement;

20 Figure 4 is a portion of a finished roof indicating the use of shingles according to the invention in applying one design to the roof as a whole;

Figure 5 indicates a second design; and

Figures 6 and 7 indicate other designs.

25 In the embodiment of the invention selected for illustration, the shingle 10 of Figure 1 is white, and the shingle 12 of Figure 2 has been indicated as brown. The shingle A of Figure 3 is divided into two portions: a left hand portion 14 colored white, and a right hand portion 16 colored brown, the two portions meeting along the center line 18 of the shingle. The shingles shown are of slightly greater length than width, and when laid close together in continuous rows with an exposure equal to half their width, the excess length insures that the square edge of each shingle will project a little above the lower edge of the shingle in the second row above to afford complete protection against the weather.

30 Using an assortment of the three different kinds of shingles illustrated in Figures 1, 2 and 3, it is possible to build up on a completed roof any desired pattern or configuration by the proper placement of the different kinds of shingles. The advantage of the third type of shingle indicated as A is that vertical lines dividing white and brown areas 50 on the roof can be made perfectly straight up

and down the roof. Thus in Figure 7 at the left hand side of the brown square there are three shingles according to Figure 3, each placed with its brown portion 16 to the right, while at the right hand side of the same square, there are four identical shingles each placed with the brown area 16 to the left. This defines the sides of the square in lines equally straight and well defined with the horizontal lines at the top and bottom. In this way any desired arrangement of rectangles of either color may be built up on a background of the other color.

35 In Figure 6 I have indicated a rectangle that is not square built up in brown on a white background in the same way as the square of Figure 7.

Figure 4 illustrates a fairly close approximation of an arc of a circle such as might be employed in building up the letter O on a large scale, and Figure 5 illustrates part of a symmetrical eight sided figure that might also be employed to serve for the letter O.

40 It will be apparent that even roofs of relatively small sizes would be large enough to accommodate letters as large as those indicated by Figures 4 and 5. Furthermore, the larger the roof and its design, the more inconspicuous will be the small serrations along the edges of the areas defining the letters or other insignia.

45 Without further elaboration the foregoing will so fully explain my invention that others may, by applying knowledge current at the time of application, readily adapt the same for use under various conditions of service.

I claim:

50 1. A design roof having design areas with straight vertical edges, said roof being made up of overlapping courses of three kinds of rectangular shingles, a first kind having a

first color, a second kind having a second color, and a third kind divided vertically in the middle into two equal portions, one portion being of said first color and the other of said second color.

5 2. A design roof made up of overlapping courses of three kinds of rectangular shingles, a first kind having a first color, a second kind having a second color, and a third kind divided vertically in the middle into two equal portions, one portion being of said first color and the other of said second color, whereby design areas of solid color may be laid with straight vertical edges, and inclined edges offset by sawteeth only half as large as the exposed area of a shingle.

10 3. A design roof made up of overlapping courses of three kinds of rectangular shingles only, a first kind having a first color, a second kind having a second color, and a third kind divided vertically in the middle into two equal portions, one portion being of said first color and the other of said second color, said shingles being laid with an exposure 15 equal to half their width; whereby design areas of solid color may be laid with straight vertical edges, and with inclined edges offset by substantially square sawteeth only half as large as the exposed area of a shingle.

20 4. A design roof made up of overlapping courses of three kinds of shingles, a first kind having a first color, a second kind having a second color, and a third kind divided vertically in the middle into two equal portions, 25 one portion being of said first color and the other of said second color, said roof including design areas of solid color having straight vertical edges.

30 5. A design roof having design areas with straight vertical edges, said roof being made up of overlapping courses of three kinds of rectangular shingles, a first kind having a first color, a second kind having a second color, and a third kind divided vertically into 35 two portions, one portion being of said first color and the other of said second color.

40 In testimony whereof I hereunto affix my signature.

ROBERT MACLEAN.
